ELECTRICAL TAP CONNECTOR

Harry Russell Bethune, Scotch Plains, N. J., assignor to
The Thomas & Betts Co., Elizabeth, N. J., a corpora-
tion of New Jersey

Application October 2, 1957, Serial No. 47,944

Term of patent 14 years

(Cl. D26—1)

Fig. 1 is a perspective view of an electrical tap connector, showing my new design;

Fig. 2 is a top plan view;

Fig. 3 is a front elevational view, the rear being sub-
stantially a mirror image thereof;

Fig. 4 is a side elevational view, the opposite side being
substantially a mirror image thereof;

Fig. 5 is a bottom plan view;

Fig. 6 is an exploded fragmentary top perspective view;
and

Fig. 7 is an exploded fragmentary bottom perspective
view thereof.

I claim:

The ornamental design for an electrical tap connector,
as shown and described.
